Certificate

Patent No. D. 242,030

Patented October 26, 1976

Alvin L. Thomson and Curtis L. Luce

Application having been made by Alvin L. Thomson and Curtis L. Luce, the inventors named in the patent above identified, for the issuance of a certificate under the provisions of Title 35, Section 256, of the United States Code, deleting the name of Curtis L. Luce as a joint inventor, and a showing and proof of facts satisfying the requirements of the said section having been submitted, it is this 31st day of May 1977, certified that the name of the said Curtis L. Luce is hereby deleted from the said patent as a joint inventor with the said Alvin L. Thomson.

FRED W. SHERLING,
Associate Solicitor.
